UNITED STATES PATENT OFFICE

ROBERT ROWSE DUNLOP, OF COLUMBUS, OHIO, ASSIGNOR TO THE JEFFREY MANUFACTURING COMPANY, OF COLUMBUS, OHIO, A CORPORATION OF OHIO

ELECTROMAGNET

Application filed January 26, 1924. Serial No. 688,854.

The present invention relates to certain new and useful improvements in electromagnets and method of making same, and particularly to that class of electromagnets which is adapted to extend parallel to the cylinder of an electric controller in close proximity to the contact fingers to extinguish the arcs forming at the points of contact between said fingers and the cylinder.

As heretofore constructed, electromagnets of the class referred to have been formed by winding a wire of suitable cross section upon a mandrel to form a helical conductor having the desired magnetic characteristics, the ends of which were adapted to be clamped or soldered into suitable connecting devices associated with the apparatus of which the magnet forms a part. Such a coil is more or less distorted by removal from the mandrel, and the character of its terminal connections renders its form still more irregular, materially increasing the difficulty of assembling the apparatus.

It is the especial object of this invention to provide an electromagnet of improved construction and a method of producing such magnet as to insure uniformity of dimensions, combined with economy of manufacture and convenience of installation.

The device and the method by which I attain these objects is fully set forth in the following specification and illustrated in the accompanying drawings, of which—

Fig. 1 is an elevation of the preferred embodiment of my invention, the insulating shield being partially broken away to reveal the construction of the conductor coil.

Fig. 2 is a sectional view taken along the longitudinal central plane of the device illustrated in Fig. 1.

Like numerals refer to similar parts in the several figures.

As illustrated in the drawings, my improved electromagnet comprises a metallic tube 1, preferably a copper tube, through the wall of which is cut a slot 2, preferably disposed in spiral form, to form a helical conductor adapted to generate a magnetic field when an electric current flows through such conductor from one end of the tube to the

other. The slot 2 preferably terminates near the ends of the tube, thereby forming a closed ring 3 at each end of the coil, and into these rings project the lugs 4, preferably cylindrical and preferably formed integral with the supporting brackets 5. The lugs 4 are split longitudinally and are fitted with expansion members, here shown as screws 6, of such shape and proportion that when said members are driven inwardly, said lugs will be expanded into forced engagement with the walls of the rings 3 to secure the magnet coil to the supporting brackets and insure good electrical connections between these parts.

It will be noted that a threaded bore is provided in each supporting member and its associated split lug 4 and terminates in a tapered portion adapted to cooperate with the tapered end of the screw 6 to cause expansion of the split lugs when the screws are driven home.

In service, the supporting brackets 5 are connected with the circuits of the apparatus of which this magnet forms a part, and the flow of electric current from one supporting bracket to the other through the conductor 1 generates the desired magnetic field in the manner which is well understood in the art.

A suitable iron core 7 is positioned inside the coil 1 to concentrate the magnetic field, and a suitable insulating cylinder 8 of suitable material, preferably a non-combustible insulating material, surrounds the core 7 to electrically separate it from the conductor 1. Suitable insulating disks 9 are provided at each end of the core 7 to prevent its electrical connection with the supporting lugs 4, and a cylindrical shield 10 of any suitable material, preferably a non-combustible insulating material, protects the magnet from external short circuit.

By the construction above described, and following my method, extreme accuracy, both of form and dimensions, is secured, permitting the convenient use in assembling the magnet of accurately fitting, previously formed insulating units. This results in extreme durability and efficiency combined with economy of manufacture and convenience of installation.

Such mechanical changes and the adoption of equivalent mechanical expedients for those herein illustrated as involve only mechanical skill may be made and still be within the range of my invention.

I claim:-

1. In an electromagnet, the combination of a helical conductor, and a support therefor having an expansible device projecting into the end of said conductor, and means for expanding said device.
2. In an electromagnet, the combination of a helical conductor, a support having an integral expansible plug fitting within an end of said helical conductor, a screw carried by said support for expanding said plug, and a nut carried by said screw and abutting said support.
3. In an electro-magnet the combination of a metallic tube having a spiral slot formed in its wall throughout its major middle portion and terminating short of the ends thereof to provide unslotted end portions, expansible supporting devices projecting into the unslotted ends of said tube, and means for expanding these devices in the unslotted ends.
4. In an electro-magnet the combination of a metallic tube having a spiral slot formed in its wall throughout its major middle portion and terminating short of the ends thereof to provide unslotted end portions, a plurality of segments forming an annular plug in the unslotted ends of said tube, and means for expanding said segments to grip said unslotted ends interiorly.
5. In an electro-magnet the combination of a metallic tube having a spiral slot formed in its wall throughout its major middle portion and terminating short of the ends thereof to provide unslotted end portions, a plurality of threaded segments forming an annular plug in the unslotted ends of said tube, and a screw having a wedge-shaped portion engaging said plug members to expand the same and grip the unslotted ends of the tube interiorly.
6. In an electro-magnet the combination of a metallic tube having a spiral slot formed in its wall throughout its major middle portion and terminating short of the ends thereof to provide unslotted end portions, a plurality of threaded segments forming an annular plug in the unslotted ends of said tube, a screw having a wedge-shaped portion engaging said plug members to expand the same and grip the unslotted ends of the tube interiorly, and supports formed integral with said plug members.
7. In an electromagnet, the combination of a helical conductor, a tubular insulating member surrounding said conductor and being coextensive therewith, and supports frictionally engaging within the ends of said conductor and abutting the ends of said insulating member.
8. In an electromagnet, the combination with a helical conductor, a tubular insulating member mounted upon said conductor and being coextensive therewith, a support for each end of the magnet having an expansible device projecting into its respective end of said conductor, and said supports being arranged to abut the ends of said tubular insulating member.
9. An electro-magnet coil comprising a helical conductor, supporting means extending axially thereof and into the ends of the same for establishing electrical connection therewith, and a tubular insulating member surrounding said conductor and having its ends abutting the supporting means to retain said member in position.
10. An electro-magnet coil comprising a helical conductor, supporting devices extending axially thereof and into the ends of said conductor for establishing electrical connection therewith, a core for the conductor, and insulating devices arranged between the ends of the core and said supporting devices.
11. An electro-magnet coil comprising a helical conductor, supporting devices extending co-axially thereof and into opposite ends of said conductor for establishing electrical connection therewith, a core for the conductor, an insulating sleeve receiving said core to space the same from the conductor, and insulating discs arranged between the ends of said sleeve and said supporting devices.
12. In an electro-magnet, a helical conductor, and a support therefor having split cylindrical lugs projecting into the end of said conductor, and means for expanding said split lugs.
13. In an electromagnet, the combination of a helical conductor, a support therefor having a split cylindrical lug projecting into the end of said conductor, said lug having a threaded bore and tapered portion, and a screw mounted in said bore and having a tapered end to cooperate with the tapered portion of said lug for expanding the same.
14. An electromagnet coil comprising a tubular helical conductor, supporting members extending co-axially thereof and into the ends of said conductor for establishing electrical connection therewith, and a tubular insulating member surrounding said conductor and having its ends abutting said supporting members to retain said insulating member in position.
15. An electrical device comprising a helical conductor, and combined supporting and conductor means extending axially thereof and into the end of the same for supporting and making an electrical contact with said conductor.
16. An electrical device comprising a metal tube having a spiral slot formed in its wall throughout its major middle portion and

terminating short of the ends thereof to provide a helical conductor with unslotted end portions, and supports extending axially into said unslotted ends and establishing an electrical connection therewith.

In testimony whereof I have hereunto set my hand.

ROBERT ROWSE DUNLOP.
